UMBRELLA HOLDER

Millard Merz, Jr., Woodholme Ave., Pikesville, Md.

Filed Aug. 4, 1964, Ser. No. 81,164

Term of patent 14 years

(Cl. D58—2)

FIG. 1

FIG. 2

FIGURE 1 is an elevation of an umbrella holder;
FIGURE 2 is a side elevation of an umbrella holder,
illustrating the umbrella receiving opening.

The design is characterized by the shorter and longer tapering sides with an opening into the interior of the umbrella holder along the shorter tapering side, by the greater angle of taper of the shorter side relative to the angle of taper of the longer side, and further by the grommet at the upper end thereof offset from center in a direction away from the shorter tapering side.

I claim:

The ornamental design for an umbrella holder, as shown and described.
